UNITED STATES PATENT OFFICE.

FRED R. PATCH, OF RUTLAND, VERMONT.

DERRICK.

No. 899,758.

Specification of Letters Patent. Patented Sept. 29, 1908.

Application filed July 22, 1908. Serial No. 444,838.

To all whom it may concern:

Be it known that I, FRED R. PATCH, citizen of the United States, residing at Rutland, county of Rutland, and State of Vermont, have invented certain new and useful Improvements in Derricks, of which the following is a specification, reference being had therein to the accompanying drawing.

This invention relates to a derrick, and particularly to a fall line connection for the main hoisting line from the boom.

The invention has for an object to provide a carriage disposed between the base of the derrick mast and the hoisting power and connected with the hoisting line carried by the boom of the mast so as to permit the lifting of the load to the desired height without necessarily increasing the height of the mast, as the travel of the carriage upon the ground may be for any desired extent necessary to secure the desired lift at the upper end of the boom.

A further object of the invention is to provide a novel and improved construction of carriage adapted for connection to the hoisting line and fall line and provided with sheaves comprising a fall block in a tackle connection between the hoist line and power.

Other and further objects and advantages of the invention will be hereinafter fully set forth and the novel features thereof defined by the appended claims.

In the drawing:—Figure 1 is an elevation of the invention applied to a derrick; Fig. 2 is a plan of the carriage; Fig. 3 is an end elevation at the left of Fig. 2. Fig. 4 a plan and Fig. 5 an elevation of the fall line connection.

Like numerals refer to like parts in the several views of the drawing.

The numeral 10 designates the mast of the derrick which may be of any desired construction and suitably supported in position by means of the guy ropes 11 extending therefrom to a fixed point. This mast is provided at its base with the usual bull wheel 12 and has the boom 13 pivotally mounted thereon at 14, the upper end 15 of this boom being connected by tackle line 16 with the mast block 17 from which connection the boom fall line 18 extends to the hoisting power as indicated at 19. The disposition of this power relative to the mast determines the arrangement of this line, for instance, it 50 may be carried by the block 20 disposed on

the post or mast 21 and thence to the usual winding drum 22. The boom is provided at its upper end with the bearing sheave 23 over which the main hoistline extends. In the arrangement of the line here shown for heavy 60 weights, one end thereof is secured to the boom at 25 and the loop thereof carries the connecting block 26 to which the weight is attached. In the lifting of lighter weights this block may be connected to the single 65 end of the line as usual in the art. The stay line 24 passes over the sheave 27 at the lower end of the boom and thence over the guide sheave 28 at the base of the mast disposed to bring the line 24 into a horizontal plane 70 where it is attached to the carriage 29. From this carriage the fall line 30 extends to the hoisting drum 31 of the power 19, this line 30 being connected at 32 to the carriage and extending thence to the fixed tackle 75 blocks 33 and thence returning over the sheaves 34 upon the carriage to the winding drum 31 so as to secure the necessary pull and length of lift for the load relative to the height of mast and boom. This carriage is 80 mounted upon the tracks or ways 35 supported in any desired manner and having intermediate of the rails thereof at suitable points horizontally disposed bearing rollers 36 adapted to support any slack in the fall 85 line when the same is being overhauled. These rollers are pivotally mounted in suitable blocks 37 at the opposite ends thereof.

The carriage 29 comprises a frame formed of parallel longitudinally extending straps or 90 bars 38 mounted upon the axles 39 which extend transversely thereof. Upon the outer ends of these axles the carrier wheels 40 are mounted to travel on the tracks 35, while at one end of the carriage the frame bars 38 are 95 connected by a cross bolt 41 with the hoist line connection 48. The opposite ends of these bars are spaced apart by blocks 42 and connected by cross pins 43. The sheaves 34 are each rotatably mounted upon the axle 39 100 and may be arranged in any desired position thereon relative to the multiple of the fall line to be carried by the carriage which forms the fall block of the tackle connection. In the present illustration two sheaves are 105 disposed upon each axle of the carriage. These sheaves are each surrounded by a line shield or guard 44 by which the fall line is retained in proper position thereon and prevented from disengagement. The shields are mount- 110

ed upon the frame at one side of the axles and completely surround a portion of the sheaves 34. The frame is also provided at 45 with a track lock extending downward 5 therefrom, as shown in Figs. 2 and 3 to engage beneath the tread of the rails 35 and thus prevent either lateral or vertical displacement of the carriage from the rails under hoisting strain.

10 Any desired means for overhauling or the return movement of the carriage may be provided, such, for instance, as the weight of the blocks or connections carried by the main hoisting line, but a desirable connection 15 for providing a positive overhauling action is secured through the overhaul line 50 which is attached to the carriage at 51 and extends over a block 52 fixed adjacent the base of the mast and thence extends to the winding 20 drum 53 which may be controlled in any manner. It is here shown as mounted upon the shaft of the drum 31 and of less diameter. In order to secure the necessary direction of 25 travel of these lines the main hoist rope is attached to the under side of its drum and the overhaul rope attached to the upper side of its drum so that when one is winding in the other is playing out.

In the operation of the invention it will be 30 seen that the fall line tackle provides the necessary pull for the hoist rope carried by the boom and may be formed of any desired length so as to secure the maximum length of lift of which the predetermined length of 35 the boom is capable without requiring additional height of the mast which has heretofore been necessary when the fall line was disposed thereon thus materially economizing in the cost of the derrick and providing 40 a more efficient, substantial and accessible disposition of the fall block, as the carriage arrangement provides for any desired multiple of the fall line thereon and exerts the minimum of friction in its operation. By a 45 proper arrangement of the tackle between the hoisting power and carriage a limited travel of this carriage upon the track can be utilized to effect the desired height of lift. The construction of this carriage also provides means by which the sheaves are directly 50 mounted upon the axles thereof and the rope retained thereon by shields, while any movement laterally or vertically is resisted by the track locks. During the hoisting operation the carriage moves toward the hoisting power and in the overhauling or return movement the necessary power is provided by the overhaul line. While the track has been herein shown as extending from the 55 derrick to the power this is not necessary in all cases as the track need only be of sufficient length to obtain the height of lift desired and can be disposed at any desired points intermediate or between the mast base 60 and power.

Having described my invention and set forth its merits, what I claim and desire to secure by Letters Patent is:—

1. A derrick comprising a mast and boom, a hoist line extending from the outer end of 70 said boom to the base of said mast, a hoisting power, a carriage connected with said line and mounted to travel between the mast base and power, and a tackle extending between said carriage and power. 75

2. A derrick comprising a mast and a boom, a hoist line extending from the outer end of said boom to the base of said mast, a hoisting power, a carriage connected with 80 said line and mounted to travel between said mast base and power, and a tackle extending from said carriage over a fixed block and thence over a sheave upon said carriage to said power.

3. A derrick comprising a mast and a boom, a hoist line extending from the outer end of said boom to the base of said mast, a hoisting power, a carriage connected with 85 said line and mounted to travel between the mast base and power, a tackle extending between said carriage and power, track rails for said carriage, and bearing rollers intermediate of said rails.

4. A derrick comprising a mast, a boom pivoted thereon and having a guide sheave 95 at each end, a hoist line extending over said sheaves to the base of the mast, a hoisting power, a carriage connected to said line and mounted to travel between the mast base and power, and a connection between said 100 carriage and power.

5. A derrick comprising a mast, a boom pivoted thereon and having a guide sheave at each end, a hoist line extending over said 105 sheaves to the base of the mast, a hoisting power, a carriage connected to said line and mounted to travel between the mast base and power, tackle sheaves mounted upon said carriage, and a tackle extended between said carriage and power. 110

6. In a derrick, a fall block carriage comprising a frame having an axle mounted thereon, carrier wheels on said axle, a sheave rotatably mounted on said axle, and hoist and power line connections with said carriage. 115

7. In a derrick, a fall block carriage comprising a frame, an axle mounted thereon, carrier wheels on said axle, a sheave rotatably mounted on said axle, hoist and power 120 line connections with said carriage, and a shield surrounding said sheave.

8. In a derrick, a fall block carriage comprising a frame having an axle mounted thereon, carrier wheels on said axle, a sheave rotatably mounted on said axle, hoist and power 125 line connections with said carriage, and a track lock mounted upon said carriage and extended beneath the tread of one of the rails upon which said carriage travels. 130

9. In a derrick, a fall block carriage comprising a frame formed of parallel members connected together at each end, hoist and fall line connections with said frame, axles 5 mounted in said frame and provided with carrier wheels, and sheaves mounted upon said axles intermediate of the parallel frame members.

10. In a derrick, a fall block carriage comprising a frame formed of parallel members connected together at each end, hoist and fall line connections with said frame, axles 10 mounted in said frame and provided with carrier wheels, sheaves mounted upon said 15 axles intermediate of the parallel frame members, and shields surrounding a portion of said sheaves and supported by the frame at one side of the axis of the sheave.

11. In a derrick, a fall block carriage comprising a frame formed of parallel members connected together at each end, hoist and fall line connections with said frame, axles 20 mounted in said frame and provided with carrier wheels, sheaves mounted upon said 25 axles intermediate of the parallel frame members, shields surrounding a portion of said sheaves and supported by the frame at one side of the axis of the sheave.

12. In a derrick, a mast and boom, a hoist 30 line extending from the outer end of the boom to the base of the mast, a hoisting power, a track disposed between said power and mast base, a carriage mounted upon said track and connected at one end with said 35 line, and a tackle connection between the opposite end of said carriage and said power.

13. In a derrick, a mast and boom, a hoist

line extending from the outer end of the boom to the base of the mast, a hoisting power, a track disposed between said power 40 and mast base, a carriage mounted upon said track and connected at one end with said line, sheaves rotatably mounted upon said carriage, and a tackle connection extending from one end of said carriage over a 45 fixed block and thence over the sheave upon said carriage to the power.

14. In a derrick, a mast and boom, a hoist line extending from the outer end of the boom to the base of the mast, a hoisting 50 power, a track disposed between said power and mast base, a carriage mounted upon said track and connected at one end with said line, sheaves rotatably mounted upon said carriage, a tackle connection extending from one end of carriage over a fixed block and thence over the sheave upon said carriage to the power, and means carried by said carriage to prevent vertical and lateral movement thereof upon the track rails. 55

15. A derrick comprising a mast and boom, a hoist line extending from said boom to the base of said mast, a hoisting power, a carriage connected with said line, a tackle extending between said carriage and power, 60 and an overhaul line extending from said carriage over a block adjacent the mast and thence to a power device. 65

In testimony whereof I affix my signature in presence of two witnesses.
